UNITED STATES PATENT OFFICE.

WILLIAM C. CODD, OF BALTIMORE, MARYLAND.

GRATE-BAR FOR MARINE AND STATIONARY BOILERS.

1,212,018.

Specification of Letters Patent.

Patented Jan. 9, 1917.

Application filed May 3, 1916. Serial No. 95,218.

To all whom it may concern:

Be it known that I, WILLIAM C. CODD, a citizen of the United States, residing at Baltimore, in the State of Maryland, have 5 invented certain new and useful Improvements in Grate-Bars for Marine and Stationary Boilers; and I do hereby declare the following to be a full, clear, and exact description of the invention, such as will enable others skilled in the art to which it 10 pertains to make and use the same.

The invention relates to improvements in grate bars for marine and stationary boilers.

The object of the present invention is to 15 improve the construction of grate bars and to provide a simple, practical and efficient grate bar, of strong, durable and comparatively inexpensive construction adapted to afford an increased draft and capable of 20 deflecting the fire tools to avoid breaking the grate bars.

A further object of the invention is to provide a grate bar of this character having 25 projections or lugs provided with a relatively sharp downward taper and rounded at the side and end edges so as to tend to drop ashes as well as deflect the fire tools.

With these and other objects in view, the 30 invention consists in the construction and novel combination of parts hereinafter fully described, illustrated in the accompanying drawing, and pointed out in the claim here- 35 to appended; it being understood that various changes in the form, proportion, size and minor details of construction, within the scope of the claim, may be resorted to without departing from the spirit or sacrificing any of the advantages of the invention.

In the drawing Figure 1 is a plan view of 40 a double grate bar constructed in accordance with this invention, Fig. 2 is a side elevation of the same, Fig. 3 is a transverse sectional view on the line 3-3 of Fig. 1, Fig. 4 is an end elevation.

45 Like numerals of reference designate corresponding parts in the several figures of the drawing.

In the accompanying drawing in which 50 is illustrated the preferred embodiment of the invention, the grate bar which may be made either single or double, when double comprises in its construction a pair of par-

allel longitudinal bars or body portions 1 connected by transverse end bars or members 2, and also by an intermediate centrally 55 arranged connecting member 3. The end bars or members 2 may be constructed of any suitable exterior configuration to suit requirements and as shown are provided with vertical projecting enlargements 4 and form 60 horizontal lower faces or shoulders 5 which are adapted to rest upon suitable supports. The lugs or enlargements 4 provide intervening end recesses 6. Each of the longitudinal bars or body portions 1 is provided 65 at opposite sides with laterally projecting lugs 7 which as illustrated in Fig. 2 of the drawing are provided with a relatively sharp downward taper forming relatively wide intervening recesses 8 and adapted to 70 increase the draft. The lugs are rounded at their upper faces and side edges to present a transversely curved convex upper face 9 and the outer ends of the lugs are rounded at 10 forming rounded outer vertical end 75 faces. The rounding of the lugs at both the outer vertical end faces and the upper faces tends to deflect the fire tools to prevent breaking of the grate bars and they also serve to cause the lugs to tend to drop the 80 ashes. The lugs of the parallel bars or body portions are arranged in staggered relation, each bar or body portion having its lugs located opposite the spaces or intervals between the lugs of the other bar or body portion. 85

The double grate bars are maintained in spaced relation and are also connected and reinforced by the transverse connecting members 3 which are composed of straight 90 side sections 11 arranged in different transverse planes and connected by a diagonally disposed central portion 12 and provided with diagonally extending terminal portions 13 having flat end faces 14. The longitudinal bars 1 are provided in their upper faces with grooves 15 extending longitudinally of the grate bars. 95

What is claimed is:—

A grate bar of the class described including spaced parallel bars or body portions provided at intervals with laterally projecting lugs arranged in staggered relation and having rounded top and outer end faces 100

and tapered downwardly to a relatively sharp lower edge and a transverse connecting portion formed integral with the bars or body portions and consisting of straight 5 end sections arranged in different transverse planes and connected by a diagonally disposed central portion, said end sections having reversely extending diagonally disposed

outer terminals projecting beyond the lugs and having flat end faces.

In testimony whereof I affix my signature in presence of two witnesses.

WILLIAM C. CODD.
